UNITED STATES PATENT OFFICE

VADEN W. MASON, OF BROOKNEAL, VIRGINIA

STEAM GENERATING PLANT

Application filed August 5, 1930. Serial No. 473,208.

This invention relates to a steam generating plant and has relation more particularly to a plant of this kind embodying the general principle of flash generation.

5 The invention has for an object to provide a rotating part provided with a plurality of circumferentially spaced steam generating units each including a hot plate, together with means for intermittently rotating said part 10 to bring the units successively to a predetermined location for steam generation and with means for supplying water to the hot plate during the period the unit is at such location.

15 The invention consists in the details of construction and in the combination and arrangement of the several parts of my improved steam generating plant whereby certain important advantages are attained and 20 the device rendered simpler, less expensive and otherwise more convenient and advantageous for use, as will be hereinafter more fully set forth.

25 The novel features of my invention will hereinafter be definitely claimed.

In order that my invention may be the better understood, I will now proceed to describe the same with reference to the accompanying drawings, wherein:

30 Figure 1 is a view in top plan of a steam generating plant constructed in accordance with an embodiment of my invention, the associated heating units being indicated by broken lines and a coacting engine being 35 shown in fragment;

Figure 2 is a vertical sectional view taken through the center of the structure as illustrated in Figure 1 including the engine with certain of the parts in elevation;

40 Figure 3 is a fragmentary view in top plan and of somewhat a diagrammatic character illustrating certain of the features of construction for effecting the desired intermittent rotation of the rotating member;

45 Figure 4 is a fragmentary view partly in

section and partly in plan of additional mechanism comprised in the means for rotating the rotatable member;

Figure 5 is a fragmentary view in side elevation illustrating in detail a portion of 50 the assembly for effecting an intermittent rotation of the rotatable member;

Figure 6 is an enlarged detailed sectional view taken substantially on the line 6—6 of Figure 3;

55 Figure 7 is an enlarged detailed sectional view taken substantially on the line 7—7 of Figure 3;

Figure 8 is an enlarged detailed sectional view taken substantially on the line 8—8 of 60 Figure 2.

As disclosed in the accompanying drawings, B denotes a base or supporting structure which rotatably supports an upstanding or vertically disposed shaft 1. Keyed or 65 otherwise fixed to the shaft 1 is the hub 2 of a rotating member M. Radiating from the hub 2 are the spokes 3 carrying at their outer ends the relatively broad annular rim 4. At equidistantly spaced points therearound the 70 rim 4 is provided with the openings 5 and secured to the rim 4 to the rear of each of the openings 5 is a casting 7. The casting 7 is so formed as to provide a pocket 8 registering with the opening 5 and the water 75 jacket 9. The casting 7 is in two parts, one part 10 constituting the wall of the pocket 8 and the second part 11 constituting the wall of the jacket 9.

Extending through each of the openings 80 5 into the adjacent pocket 8 is a hot plate 12, said plate conforming in a general way to the configuration of the pocket 8 but spaced from the wall 10. The hot plate 12 is provided at each extremity with an end 85 plate 14 formed therewith and which is bolted, as at 15, or otherwise secured to the rim 4 within the opening 5. The hot plate 12 has disposed therethrough at desired points the openings 16 for the passage of the steam 90

resulting from the water dropping upon the inner surface of the heated plate 12 from within the jacket 9. The jacket 9 is adapted to be constantly filled with water and the jacket is so formed as to substantially surround the wall 10 so that water within the jacket 9 will absorb such heat as may pass through the wall 10 to effect a preheating of the water within the jacket 9.

10 Rotating with the member M and positioned entirely above the chambers 8 is a supply tank T of predetermined capacity and this tank T is in communication with the upper portion of each of the jackets 9 through 15 the medium of a pipe line 17 in which is interposed a non-return valve 18 indicated by broken lines in Figure 2 and which non-return valve may be of any type preferred.

The water as placed within the tank T fills 20 the jackets 9, and each of the jackets 9 is in communication with a pocket 8 through the medium of a series of openings 19 provided through the upper portion of the part 10. These openings 19 communicate with 25 a groove or channel 20 formed in the upper surface of the part 10 and in which groove or channel is snugly engaged the lower portion of a cylindrical valve member 21. This valve member 21 extends through and is rotatably supported by the side walls of the jacket 9 and one end portion of the valve member 21 extends beyond a side wall of the jacket as particularly illustrated in Figure 30 8. This extended portion of the valve member 21 has fixed thereto an upstanding rock arm 22 and coacting with this rock arm 22 and an outstanding lug 23 or the like carried by the adjacent side wall of the jacket, is a spring 24 which serves to normally maintain 35 the openings 25 through the valve member 21 out of register with the openings 19 in the part 10 of the casting 7. An intermediate portion of the spring 24 is coiled, as at 26, around the adjacent extended end 40 portion of the valve member 21.

Just before a pocket 8 is brought into register with the intake port 27 of an engine E or the like, the rock arm 22 is brought into contact with the horizontally inclined or cam 50 arm 28 which serves to rock the arm 22 sufficiently to bring the openings 25 of the valve member 21 into register with the openings 19 so that the water within the jacket 9 will pass through the openings 19 and fall upon 55 the preheated plate 12 resulting in immediate generation of steam which will pass into the port 27 of the engine and from there to its work.

After a predetermined time, the pocket 60 8 will be moved away from register with the intake port 27 and as the rock arm 22 passes from the cam arm 28 the spring 24 will operate to return the valve member 21 into its normally closed position.

65 The arm 28 hereinbefore referred to is car-

ried by the lower portion of a vertically disposed arm 29 pivotally mounted, as at 30, at a desired point between its ends to a bracket 31 or the like carried by the engine E. The extremity of the arm 29 remote from the horizontal cam arm 28 is operatively engaged through the pitman 32 with a governor mechanism G whereby as the speed of the engine E increases or decreases the arm 28 will be correspondingly moved into or out of the path of travel of the rock arm 22 thus assuring an effective regulation of the feed of the water to a hot plate 12.

The inner portion of the pocket 8 has in communication therewith an upstanding pipe 33 positioned entirely within the jacket 9 and terminating adjacent the top of such jacket. The upper end of this pipe 33 is normally closed by a flap valve 34. This pipe 33 is provided in the event there should be 35 abnormal back pressure within the pocket 8.

Mounted upon the shaft 1 for rotation therewith and located between the base B and the hub 2 of the member M is a head or casting H provided at spaced points around its periphery with the radially directed pockets 35 in each of which is engaged an end portion of an elongated arm 36 there being one arm 36 for each generator. The portion of the arm 36 within its pocket 35 is mounted, as at 37, for vertical swinging movement. The top wall of the inner portion of the pocket 35 is so formed, as at 38, to limit the downward movement of the outer portion of the arm 36 below substantially the horizontal.

Each of the arms 36 is of a length to overlie the upper stretch of an endless chain 39 travelling over the top surface of the base B and which chain or endless member 39 passes around the suitably positioned sprocket wheels 40. One of the sprocket wheels 40 is mounted on a shaft 41 which is also in driven connection through the endless member or chain 42 or the like with a rotatable part of the engine E so that the endless member or chain 39 will be driven at a predetermined rate of speed.

Carried by adjacent links of the chain 39 are the lugs 43 which, when applied, afford a wedge member which as it passes under the outer end portion of an arm 36 raises the same from within the notch or recess 44 in a holding flange 45 carried by the base B. When an arm 36 is engaged within a notch or recess 44 a pocket 8 is maintained in desired register with the intake port 27 of the engine E. However, as the endless chain 39 travels the wedge medium afforded by the lugs 43 passes under the arm 36 and raises the same sufficiently to disengage the arm 36 from within the notch or recess 44. At this time a shoulder 46 carried by the innermost lug 43 contacts with the arm 36 with the result that the shaft 1 is rotated sufficient to 120

bring a succeeding pocket 8 into register with the intake port 27. Just before a succeeding arm 36 is brought into position to be engaged within the notch or recess 44 of the holding flange 45, the preceding arm 36 rides up a lifting flange 47 also suitably mounted upon the base B so that at the time one arm 36 is having locking engagement within the notch or recess 44 of the flange 45 the arm 36 in advance thereof is freed from the shoulder 46 so that the chain 39 continues its travel unhampered or without obstruction. It is, therefore, believed to be self-evident that the shaft 1 will be intermittently rotated at predetermined intervals, the period of such intervals being based upon the speed of the engine as transmitted to the governor.

The plates 12 before being brought into register with the intake port 27 are subjected to a suitable heating medium herein indicated by broken lines as oil burners 48. These burners 48 may be any number desired and as the requirements of practice may determine. I also wish to be understood as not limiting myself to the use of oil burners 48 as it is within the scope of my invention to employ any heating means for the plates 12 which can be used to advantage.

From the foregoing description it is thought to be obvious that a steam generating plant constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:

1. In a plant of the class described comprising a rotatable member provided in its peripheral portion with a plurality of circumferentially spaced pockets, heat plates within the pockets, means for discharging water upon each of the plates when the pocket for said plate is at a predetermined point in the rotation of the member.

2. In a plant of the class described comprising a rotatable member provided in its peripheral portion with a plurality of circumferentially spaced pockets, heat plates within the pockets, means for discharging water upon each of the plates when the pocket for said plate is at a predetermined point in the rotation of the member, and means for heating each of said plates before water is discharged thereon.

3. In a plant of the class described comprising a rotatable member provided in its peripheral portion with a plurality of cir-

cumferentially spaced pockets, heat plates within the pockets, means for discharging water upon each of the plates when the pocket for said plate is at a predetermined point in the rotation of the member, and means for intermittently rotating the member.

4. In an engine having an intake port, a member supported for rotation with respect to said intake port, said member having pockets adapted to be intermittently brought into register with the intake port, a heat plate within each of the pockets, means for delivering water to the heat plate in a pocket when in register with the intake port, means for heating each of said plates before its pocket is brought into register with the intake port, and means for intermittently rotating the member.

5. In an engine having an intake port, a member supported for rotation with respect to said intake port, said member having pockets adapted to be intermittently brought into register with the intake port, a heat plate within each of the pockets, means for delivering water to the heat plate in a pocket when in register with the intake port, means for heating each of said plates before its pocket is brought into register with the intake port, and means for intermittently rotating the member, the major portion of a heat plate being spaced from the walls of its pocket, said plate having perforations, and water being delivered upon the rear face of the plate.

6. In an engine having an intake port and a rotatable part, a member supported for rotation with respect to the intake port, said member having pockets adapted to be intermittently brought into register with the intake port of the engine, a heat plate within each of the pockets, means for discharging water upon a heat plate when its pocket is in register with the intake port, means for heating a plate before its pocket is brought into register with the intake port, and means driven from the movable part of the engine for intermittently rotating the rotatable member.

7. In an engine having an intake port and a movable part, a member supported for rotation with respect to the intake port, said member having pockets adapted to be intermittently brought into register with the intake port of the engine, a heat plate within each of the pockets, means for discharging water upon a heat plate when its pocket is in register with the intake port, means for heating a plate before its pocket is brought into register with the intake port, means driven from the movable part of the engine for intermittently rotating the rotatable member, and means for holding the rotatable member against rotation during the period

a pocket is in register with the intake port of the engine.

8. In an engine having an intake port and a movable part, a member supported for rotation with respect to the intake port, said member having pockets adapted to be intermittently brought into register with the intake port of the engine, a heat plate within each of the pockets, means for discharging water upon a heat plate when its pocket is in register with the intake port, means for heating a plate before its pocket is brought into register with the intake port, means driven from the movable part of the engine for intermittently rotating the rotatable member, means for holding the rotatable member against rotation during the period a pocket is in register with the intake port of the engine, said last named means including an endless travelling member carrying an outstanding shoulder, and arms carried by the rotatable member with which the shoulder of the endless member contacts to intermittently rotate the rotatable member.

9. In an engine having an intake port and a movable part, a member supported for rotation with respect to the intake port, said member having pockets adapted to be intermittently brought into register with the intake port of the engine, a heat plate within each of the pockets, means for discharging water upon a heat plate when its pocket is in register with the intake port, means for heating a plate before its pocket is brought into register with the intake port, means driven from the movable part of the engine for intermittently rotating the rotatable member, means for holding the rotatable member against rotation during the period a pocket is in register with the intake port of the engine, said last named means including an endless travelling member carrying an outstanding shoulder, arms carried by the rotatable member with which the shoulder of the endless member contacts to intermittently rotate the rotatable member, and means coacting with one of said arms for holding the rotatable member against rotation during the period a pocket is in register with the intake port of the engine.

10. In an engine having an intake port and a movable part, a member supported for rotation with respect to the intake port, said member having pockets adapted to be intermittently brought into register with the intake port of the engine, a heat plate within each of the pockets, means for discharging water upon a heat plate when its pocket is in register with the intake port, means for heating a plate before its pocket is brought into register with the intake port, means driven from the movable part of the engine for intermittently rotating the rotatable member, means for holding the rotatable member against rotation during the period a pocket is in register with the intake port of the engine.

11. In an engine having an intake port and a movable part, a member supported for rotation with respect to the intake port, said member having pockets adapted to be intermittently brought into register with the intake port of the engine, a heat plate within each of the pockets, means for discharging water upon a heat plate when its pocket is in register with the intake port, means for heating a plate before its pocket is brought into register with the intake port, means driven from the movable part of the engine for intermittently rotating the rotatable member, means for holding the rotatable member against rotation during the period a pocket is in register with the intake port of the engine, and means for releasing said arm before an intermittent rotation of the rotatable member.

12. In an engine having an intake port and a movable part, a member supported for rotation with respect to the intake port, said member having pockets adapted to be intermittently brought into register with the intake port of the engine, a heat plate within each of the pockets, means for discharging water upon a heat plate when its pocket is in register with the intake port, means for heating a plate before its pocket is brought into register with the intake port, means driven from the movable part of the engine for intermittently rotating the rotatable member, means for holding the rotatable member against rotation during the period a pocket is in register with the intake port of the engine, said last named means including an endless travelling member carrying an outstanding shoulder, arms carried by the rotatable member with which the shoulder of the endless member contacts to intermittently rotate the rotatable member, means coacting with one of said arms for holding the rotatable member against rotation during the period a pocket is in register with the intake port of the engine, and means for disengaging an arm from the shoulder of the travelling member upon predetermined rotation of the rotatable member.

13. In an engine having an intake port and a speed responsive device, a rotatable member having pockets adapted to be intermittently brought into register with the intake port of the engine, means for intermittently rotating said rotatable member, a source of water supply carried by the rotatable member and in communication with each of the pockets, a heat plate within each of the pockets upon which the water discharges, means for heating each plate before its pocket is brought into register with the intake port of the engine, a rock valve for controlling the delivery of water to each of the pockets, and means under control of the speed responsive device for moving the rock valve into open position.

14. In an engine having an intake port and a speed responsive device, a rotatable member having pockets adapted to be intermittently brought into register with the intake port of the engine, means for intermittently rotating said rotatable member, a source of

water supply carried by the rotatable member and in communication with each of the pockets, a heat plate within each of the pockets upon which the water discharges, means for heating each plate before its pocket is brought into register with the intake port of the engine, a rock valve for controlling the delivery of water to each of the pockets, means under control of the speed responsive device for moving the rock valve into open position, and means for constantly urging the rock valve into closed position.

In testimony whereof I hereunto affix my signature.

15 VADEN W. MASON.
